SAMUEL McEWEN, OF LONDON, ENGLAND, ASSIGNOR TO INTERNATIONAL COMBUSTION ENGINEERING CORPORATION, OF NEW YORK, N. Y., A CORPORATION OF DELAWARE.

METHOD OF BURNING FUEL AND APPARATUS THEREFOR.

Application filed April 9, 1923. Serial No. 630,970.

To all whom it may concern:

Be it known that I, SAMUEL McEWEN, a subject of the King of Great Britain, residing in London, England, have invented a certain new and useful Improved Method of Burning Fuel and Apparatus Therefor, of which the following is a specification.

Revolving cylindrical grates have been suggested as a means for keeping the fuel stirred and exposed to the air for combustion; the fuel was to be charged at one end of the cylinder and to be burnt by the air passing between the grate bars, the products of combustion passing from the end 15 of the cylinder opposite the charging end.

According to the present invention fuel is burnt in the form of a cylindrical or equivalent layer. This is possible in a grate of the above kind and by the invention 20 fuel is distributed over the inner surface of the grate in the form of a cylindrical layer retained against the surface by centrifugal force owing to the speed of revolution of the grate.

One advantage of the invention is that the cylinder being lined with incandescent fuel the fuel forms an incandescent furnace arch 25 for aiding the ignition of the incoming fuel, a function hitherto performed by arches heated merely by radiation. The difficulty of using the common brick arch with a 30 revolving cylindrical grate is one reason why such grates have not come into use.

The invention is not limited to a cylindrical form of layer, that is to say to a cylindrical grate; the form of any other suitable figure of revolution is equivalent, such as a cone; the axis of revolution may be horizontal or inclined.

The preferred form of grate is cylindrical and since it has to be rotated at a considerable speed it should be supported in ball or roller bearings, or it may be overhung from a hollow trunnion supported in suitable 45 bearings. The fuel may be fed through such trunnion or other axial shaft carrying the grate; for instance, by means of a stationary or revolving worm within the shaft.

The distribution of the fuel over the grate 50 surface may be aided by imparting a reciprocating or other movement to the bars or to some of them, for instance by mounting these bars to slide longitudinally of the cylinder in guides under action of a cam

surface engaging projections on the bars. 55 In this manner the fuel may be caused to travel in the axial direction, the clinker and ashes being discharged from the open end of the cylinder opposite the end at which the fuel is fed.

The grate is preferably contained in a casing to which air is charged under pressure and the gaseous products leaving the cylinder in axial direction pass to the boiler or to the chamber to be heated.

In some applications it may be desirable to use a fan wheel to be rotated co-axially with the revolving grate, and placed so that the fan blades move in the space between the periphery of the grate and the casing 65 enclosing it.

The accompanying drawings illustrate a construction according to the invention, Fig. 1 being a vertical longitudinal section through a furnace having a cylindrical 75 grate, Fig. 2 is a front elevation of the furnace, parts having been broken away.

a is a perforated metal drum to each end of which is fixed a cast iron ring *b*, *c*. The external periphery of each ring constitutes a roller path and is supported on two rollers *d* mounted on shafts *e* carried by bearings *f* bolted to the frame bed-plate *g*. These shafts are driven as hereinafter described and the rollers *d* drive the drum. 85

The ring *b* is of channel section; the inner flange *b'* supports one end of the grate bars *h* and *i* which alternate with each other and form the cylindrical grate. The ring *c* is of a somewhat more complex section, having on its inner face a flange *k* which supports the ends of bars *h*. The bars *i* extend through radial slots in ring *c* and are held up therein by packing pieces *l* bolted to the ring. Before each packing piece is put in place the corresponding bar *i* is engaged by means of a notch *i'* on its edge with a ring *m*. This engagement causes the ring to revolve with the drum. Guide rollers *n* carried on the main casing *o* in different vertical planes bear against the ring *m*, and serve to maintain it in a fixed plane which is inclined to the plane perpendicular to the axis of rotation of the drum, with the result that as the drum revolves the bars *i* 100 receive a reciprocating longitudinal movement, while the bars *h* do not move in the direction of their length. 105

The feed box *p* is fixed to the main casing *o* eccentrically to the drum, the object being to feed the fuel against the descending grate bars to aid the distribution of the fuel; *q* is 5 the fuel hopper, *r* the feeding worm and *s* a fire tube for protecting the inner face of the casing *o*.

The drive is from the main shaft *t* carried in bearings *s'* on the front of the bed 10 plate *g*. The bevel gear *u* on the shaft drives the roller shafts *e* which turn the drum. A worm gear on the shaft *t* drives the shaft *v* of an eccentric *w* which gives motion to the adjustable stroke lever *x* operating the friction drive wheel *y* of the feeding worm *r*.

Openings *o'* and *o''* in the casing *o* serve for examination of the bars and their removal if necessary. A casing *z* extends 20 from the main casing *o* to the boiler brick-work and encloses the whole grate, forming a substantially air-tight chamber into which air is forced or drawn at any suitable point for combustion of the fuel.

25 Door *g'* serves for removal of riddlings and ashes which fall through the grate and door *g''* for removal of ashes and clinker discharged at the open end of the drum.

The speed at which a grate of this kind 30 should be revolved in order that the fuel may be retained by centrifugal force in its distributed condition depends on the state of subdivision of the fuel and its specific gravity. In the case of a grate 2 ft. 6 inches 35 in diameter burning Midland coal passed through a 1" mesh screen, 79 revolutions per minute were sufficient.

Having thus described the nature of the 40 said invention and the best means I know of carrying the same into practical effect, I claim:—

1. A method of burning fuel in a rotating grate having the shape of a figure of revolution, which comprises the step of both distributing the fuel in the form of a layer 45 over the inner surface of the grate and retaining it against this surface, by centrifugal force due to the speed of revolution of the grate.

50 2. A method of burning fuel in a rotating grate having the shape of a figure of revolution which comprises the step of both distributing the fuel in the form of a layer over the inner surface of the grate and retaining it against this surface by centrifugal force due to the speed of revolution of the grate and causing air to pass inwardly 55 through the layer of fuel.

3. A method of burning fuel in a rotating 60 grate having the shape of a figure of revolution, which comprises the step of both distributing the fuel in the form of a layer over the inner surface of the grate and retaining it against this surface by centrifugal force 65 due to the speed of revolution of the grate,

and causing the layer to travel in the longitudinal direction of the grate during the revolution so that ashes and clinkers are discharged from the end of the grate.

4. A method of burning fuel in a rotating 70 grate having the shape of a figure of revolution, which comprises the step of both distributing the fuel in the form of a layer over the inner surface of the grate and retaining it against this surface by centrifugal force due to the speed of revolution of the grate, causing the layer to travel in the longitudinal direction of the grate during the revolution so that ashes and clinkers are discharged from the end of the grate and 75 causing air to pass inwardly through the layer of fuel.

5. A method of burning fuel in a rotating 80 grate, having the shape of a figure of revolution which comprises feeding the fuel into the grate, and retaining it in the form of a layer against the inner surface thereof by centrifugal force due to the speed of revolution of the grate.

6. A method of burning fuel in a rotating 85 grate having the shape of a figure of revolution, which comprises feeding the fuel against the portion of the inner surface of the grate which is descending in the rotational movement, and retaining it in the 90 form of a layer against this surface by centrifugal force due to the speed of revolution of the grate.

7. A method of burning fuel in a rotating 95 grate, having the shape of a figure of revolution which comprises feeding the fuel into the grate, retaining it in the form of a layer against the inner surface thereof by centrifugal force due to the speed of revolution of the grate, and causing air to pass inwardly 100 through the layer of fuel.

8. A method of burning fuel in a rotating 105 grate having the shape of a figure of revolution, which comprises feeding the fuel against the portion of the inner surface of the grate which is descending in the rotational movement, retaining it in the form of a layer against this surface by centrifugal force due to the speed of revolution of the 110 grate, and causing air to pass inwardly through the layer of fuel.

9. A method of burning fuel in a rotating 115 grate, having the shape of a figure of revolution which comprises feeding the fuel into the grate, retaining it in the form of a layer against the inner surface thereof by centrifugal force due to the speed of revolution of the grate, and causing the layer of fuel to travel in the longitudinal direction of the grate during the revolution so that 120 ashes and clinkers are discharged from the end of the grate.

10. A method of burning fuel in a rotating 125 grate having the shape of a figure of revolution, which comprises feeding the fuel

against the portion of the inner surface of the grate which is descending in the rotational movement, retaining it in the form of a layer against this surface by centrifugal force due to the speed of revolution of the grate, and causing the layer of fuel to travel in the longitudinal direction of the grate during the revolution so that ashes and clinkers are discharged from the end of the 10 grate.

11. A method of burning fuel in a rotating grate, having the shape of a figure of revolution which comprises feeding the fuel into the grate, retaining it in the form of a 15 layer against the inner surface thereof by centrifugal force due to the speed of revolution of the grate, causing air to pass inwardly through the layer of fuel, and causing the layer of fuel to travel in the longitudinal direction of the grate during the revolution so that 20 ashes and clinkers are discharged from the end of the grate.

lution so that ashes and clinkers are discharged from the end of the grate.

12. A method of burning fuel in a rotating grate having the shape of a figure of revolution, which comprises feeding the fuel 25 against the portion of the inner surface of the grate which is descending in the rotational movement, retaining it in the form of a layer against this surface by centrifugal force due to the speed of revolution of the 30 grate, causing air to pass inwardly through the layer of fuel, and causing the layer of fuel to travel in the longitudinal direction of the grate during the revolution so that 35 ashes and clinkers are discharged from the end of the grate.

In testimony whereof I have signed my name to this specification.

SAMUEL McEWEN.
